UNITED STATES PATENT OFFICE.

FRANK APPLETON, OF PHILADELPHIA, PENNSYLVANIA, ASSIGNOR, BY MESNE ASSIGNMENTS, TO SCOTT & WILLIAMS, INCORPORATED, A CORPORATION OF MASSACHUSETTS.

DEFECTIVE-NEEDLE DETECTOR FOR KNITTING-MACHINES.

1,251,460.

Specification of Letters Patent.

Patented Jan. 1, 1918.

Application filed March 10, 1916. Serial No. 83,252.

To all whom it may concern:

Be it known that I, FRANK APPLETON, a citizen of the United States, residing in Philadelphia, Pennsylvania, have invented 5 certain Improvements in Defective-Needle Detectors for Knitting-Machines, of which the following is a specification.

The object of my invention is to provide a knitting machine with alarm and stop 10 mechanism or either of them, which will operate whenever a needle is, because of a broken butt, latch, or other defect, prevented from properly performing its stitch producing function.

15 This object I attain in the manner herein-after set forth, reference being had to the accompanying drawings, in which—

Figure 1 is a side elevation of sufficient 20 of a knitting machine to illustrate my invention;

Fig. 2 is a top view of the same;

Fig. 3 is a similar view of part of the machine on a larger scale than Fig. 2;

25 Fig. 4 is a section on the line *b*—*b*, Fig. 3, but on a larger scale;

Fig. 5 is a section on the line *a*—*a*, Fig. 2, also on a larger scale;

Fig. 6 is a view similar to part of Fig. 5, but showing some of the parts in a different 30 position from that there represented;

Fig. 7 is a face view of Fig. 5, looking in the direction of the arrow *w*;

Fig. 8 is a view similar to part of Fig. 3, but illustrating some of the elements of the 35 machine in a different position from that there represented, and

Figs. 9 and 10 are views illustrating needle defects such as would cause the operation of the mechanism which I have devised.

40 Referring in the first instance to Figs. 3, 4 and 8 of the drawings, 1 represent the usual latch needles of the machine and 2 a series of web holders which alternate with the needles and engage the sinker wales of 45 the last formed course of stitches so as to prevent rise of said stitches with the needles.

So long as the needles are functioning properly the web holders (except at the point where the stitches are being drawn) 50 occupy the position shown in Figs. 3 and 4, and engage the sinker wales between adjoining stitches, but when, by reason of a broken butt, latch, or other defect, a needle fails to properly perform its stitch produc-

ing function the knitting yarn will, usually 55 for a number of successive courses, be laid across the face of the defective needle between the stitches flanking the same, as shown in Fig. 8, and when the knitting yarn is thus disposed the effect will be to push 60 back, as shown in Fig. 8, the web holders engaged thereby, the cam which controls the web holders having a break or depressed portion as shown, for instance at *w* in Figs. 4 and 8, this depressed portion being in line 65 with certain control mechanism to be later described. Normally the butts of the web holders will travel across this gap in the cam without outward movement, but when bunched yarn tends to force a web holder 70 outwardly such movement will occur at this point. I therefore constitute said web holders the primary element of the alarm and stop mechanisms shown in Figs. 1, 2, 5, 6 and 7, and which is as follows:

75 Mounted upon one of the stationary elements of the machine so as to be susceptible of radial sliding movement thereon is a plate 4, and, as the web holders rotate with the needle cylinder, or otherwise move with 80 the needle carrier of the machine, the front edge of this plate occupies a position in contact with or in close proximity to a shoulder 3 on the back of each web holder when said web holders are in the advanced or projected position shown in Figs. 3 and 4. If, therefore, one or more of the web holders is pushed outward, as shown in Fig. 8, it will, when its shoulder 3 comes into contact with the forward edge of the plate 4, push the 85 latter outwardly, and this outward movement of the plate 4 is caused to effect the operation of the alarm and stop mechanisms.

90 The outer end of the slide 4 is notched for the reception of the upwardly projecting 95 arm 5 of a curved lever 6 which is secured to a swinging yoke 7 pivotally mounted upon the same member of the machine as the slide 4, the lower arm 8 of said lever 6 bearing upon a pin 9, which is carried by one member of a yoke 10, whose opposite member is secured to a rock shaft 11 mounted in suitable bearings on the fixed frame of the machine, as shown in Fig. 2, the connecting member of said yoke 10 normally engaging 100 a notch 12 in a bolt 13, suitably guided on the fixed frame, and serving to retain said bolt in the retracted position shown in Figs. 105

1 and 2, a spring 14 connected at one end to a pin 15 on the bolt and at the opposite end to a fixed pin 16 serving to project said bolt as soon as the latter is freed from the 5 control of the yoke 10.

Side by side on the driving shaft of the machine are three pulleys 17, 18 and 19, the pulley 17 being secured to the shaft, but the pulleys 18 and 19 being free to turn thereon, 10 said pulley 19 being the ordinary loose pulley but the pulley 18 normally receiving the driving belt and having continuous rotating motion imparted thereto.

On the left hand face of the pulley 18 15 (which is adjacent to the pulley 17) is a projecting lug 20 (Figs. 5 and 6) and on the left hand face of said pulley 17 is a swinging arm 21 pivoted at 22 and having a pin 23 which projects through a slot 24 in the 20 web of the pulley 17, and, during the ordinary operation of the machine, contacts with the lug 20 on the pulley 18, the latter therefore imparting rotating movement to the pulley 17.

25 Secured to the arm 21, however, and projecting outwardly through a notch 25 in the rim of the pulley 18, is a finger 26, and, when the bolt 13 is projected to the position shown by dotted lines in Fig. 5, said finger 30 will, as it is carried around by the pulley 17, strike said bolt 13, thereby causing the arm 21 to swing inwardly from the position shown by full lines in Fig. 7 to that shown by dotted lines in said figure, the arm being 35 held in the latter position by frictional engagement with an elastic retaining finger 27 on the web of the pulley 17.

When the arm 21 is swung inwardly it 40 carries the pin 23 out of the path of the lug 20 on the pulley 18 as shown in Fig. 6, consequently the rotation of the pulley 17 and the driving shaft of the machine will be at once arrested and will not be again resumed until the arm 21 is restored to the 45 position shown by full lines in Fig. 7, and the bolt 13 has been again retracted and held in such retracted position by engagement with the arm 10, and this cannot be done until normal knitting conditions have been 50 resumed.

On the frame of the machine is mounted 55 a gong or other form of bell 30 and pivotally mounted on the frame adjacent to said gong is a lever having arms 31 and 33, the 60 arm 31 having a hammer 32 for striking the gong when said arm 31 is swung toward the same by contact of the arm 33 of the lever with a pin 34 on the bolt 13 when the latter is moving into position to engage the clutch releasing finger 26.

At all other times a spring 35 tends to hold the arm 31 in retracted position in contact with a stop pin 36.

In Figs. 1 and 2 I have shown the rock shaft 11 as provided with another arm 37 for operating in connection with a defective yarn detector, but further reference thereto in this specification will be unnecessary, as this particular feature of my invention constitutes the subject of a separate application for patent which I have filed. 70

Although I have described my invention as combining both alarm mechanism and stop mechanism either of these can be used to the exclusion of the other, if desired. 75 When the alarm mechanism only is employed the stoppage of the machine can, on the sounding of the alarm, be effected either by manual operation of the bolt 13 or by shifting the driving belt from the pulley 80 18 to the pulley 19.

I claim:

1. In a knitting machine, the combination of the needles and web holders, a member mounted so as to engage displaced web 85 holders, a clutch releasing member, means for moving the same into releasing position, a retainer for holding it out of such position, and means whereby the movement of said web holder engaging member is caused 90 to release said retainer.

2. In a knitting machine, the combination of the needles and web holders, a slide engaging displaced web holders, a clutch releasing member, means for moving the latter 95 into releasing position, a retainer for holding it out of such releasing position, and a pivoted lever interposed between said retainer and the slide and serving to transmit movement of said slide to said retainer. 100

3. In a knitting machine, the combination of the needles and web holders, a member mounted so as to engage with displaced web holders, an alarm gong, a hammer lever 105 co-operating therewith, a lever engaging member, means for moving the same into engagement with said lever, a retainer for holding it out of such engagement, and means interposed between said retainer and said web holder engaging member whereby 110 movement of the latter is caused to release the retainer.

In testimony whereof I have signed my name to this specification, in the presence of two subscribing witnesses.

FRANK APPLETON.
